DISPLACEMENT-PUMP.

1,187,579.

Specification of Letters Patent. Patented June 20, 1916.

Application filed March 8, 1915. Serial No. 12,795.

To all whom it may concern:

Be it known that we, ELMER A. WATTS and IRWIN L. DUNN, citizens of the United States, residing at Springfield, Clark county, 5 and Marietta, Washington county, Ohio, respectively, have invented certain new and useful Improvements in Displacement-Pumps, of which the following is a specification, reference being had therein to the 10 accompanying drawing.

This invention relates to displacement pumps, and more particularly to a pump of this type for use in pumping oil. Displacement pumps have heretofore been used in 15 oil wells but it has been customary to control these pumps by hand, that is, the air was admitted at such intervals as it was thought necessary to remove the oil from the well and at the end of a pumping operation 20 the air supply was cut off and the exhaust opened. This, however, entailed not only a great deal of labor but also a loss of power. The flow of oil to an oil well is gradual and in the case of an old well which has been 25 partially exhausted, or a well having a low capacity, is not sufficient to enable the pump to be operated continuously. The pump must be operated for a period of time sufficient to exhaust the oil in the well and then 30 allowed to remain idle until sufficient oil has again accumulated in the well to warrant the operation of the pump. As there is no way of determining the amount of oil in the well the operation of the pump is neces- 35 sarily based on the estimated time that is required for the well and pump chamber to fill to the desired extent. If the air is admitted to the pump before it has filled to the desired extent there is a waste of air and 40 power. If the oil is not pumped until after the well has filled to as great an extent as it will fill there is a loss because during this period no oil enters the well. Further, the different wells in a field or group of wells, 45 will require pumping at different intervals. Hence, it will be apparent that constant attention and much labor is required to pump each well at the end of the estimated period.

An object of the present invention is to 50 overcome these difficulties and eliminate a large part of the labor necessary in the operation of the pumps; to eliminate waste of power; and to cause the wells to be promptly pumped when filled, thus eliminating loss 55 from this source.

To accomplish this it is a further object of the invention to provide means for automatically controlling the admission of air to and its exhaust from the pump; and it is a further object of the invention to mount 60 in the well an oil receptacle having means coöperating therewith to automatically admit the air when the oil has reached a pre-determined level and to exhaust the air therefrom when the oil has dropped below 65 another predetermined level.

It is also an object of the invention to provide such a pump with a valve mechanism for controlling both the inlet and exhaust of air to and from the well, which valve mech- 70 anism will be controlled by a weight.

Further, it is an object of the invention to provide means for connecting the weight with the valve after the weight has been placed in the well. 75

It is also an object of the invention to provide such a mechanism which will be simple in its construction and operation; and which will be so constructed and arranged that there will be little or no wear 80 upon the parts thereof and very little attention will be required to maintain the same in working condition.

It is also an object of the invention to prevent dirt and sand from clogging the 85 valve through which the fluid enters the pump.

In the accompanying drawings, Figure 1 is a sectional view taken vertically through a pump embodying our invention; Fig. 2 is 90 a side elevation, partly in section, of the upper portion of such a mechanism; Fig. 3 is a longitudinal, sectional view of the valve forming part of the invention; Fig. 4 is a sectional, detail view of the coupling for 95 connecting the float with the valve; and Fig. 5 is a detail view of the coupling showing the separating device.

In these drawings we have illustrated one embodiment of our invention and have 100 shown the same as mounted in an oil well having the usual casing 1 and provided at its lower end with a pocket 2 into which the oil seeps or flows from the surrounding rock. Mounted in the lower part of the well, preferably near the bottom of the pocket 2, is an oil receptacle, such as a casting 3, having therein an oil chamber which has communication with the well to permit 105 the oil to enter the chamber and rise therein 110

as it rises in the well. In the present instance, the chamber is provided in its bottom with an inlet 4, which however communicates with the interior of the chamber at 5 a point above the bottom thereof. To this end the bottom of the casing has a short tube 6 extending upwardly therefrom and provided at its upper end with a check valve 7 which will permit the oil to pass 10 through the opening 4 into the chamber, but which will prevent it from escaping from the chamber through this opening. The casing 3 which contains the oil chamber may be supported in the well in any 15 suitable manner, but preferably it is secured to the lower end of a pipe 8 which is supported at its upper end by a head 9, mounted on the outer end of the casing 1, and which constitutes an air conduit by means 20 of which air under pressure may be admitted to the oil chamber. The oil chamber also has a suitable outlet which, in the present instance, is in the form of a pipe 10 extending into the chamber and communicating 25 with the same at a point below the check valve 7 of the inlet opening. This discharge pipe communicates at its upper end with a pipe 11 which extends upwardly through the casing 1 of the well, is supported by the 30 head 9 of the casing, and, at a point above the casing, is connected with a pipe 12 leading to the tank or other receptacle for the oil. The discharge line, comprising the pipes 10 and 11, is provided at a point above 35 the chamber with a check valve 13 which prevents the oil in the pipe 11 flowing back into the chamber when the pressure therein drops. By placing the lower end of the discharge pipe 10 below the check valve 7 of 40 the inlet opening 4 any sand or grit which may be present in the oil is prevented from settling on the valve seat and interfering with the proper seating of the valve or cutting the valve seat, most of the sand, etc., 45 being carried out through the pipe 10 before it can pile up to the valve 7.

It will be apparent that the oil entering 50 the well will gradually fill the oil chamber, and, when the oil has filled this chamber to a predetermined point, air under pressure is admitted to the upper end of the cylinder, through the pipe 8, and the oil forced from the chamber through the discharge line. The admission of the air is automatically controlled, and, to this end, we have 55 provided a controlling device, which preferably is in the form of a combined inlet and exhaust valve and which is in turn controlled by the rise and fall of the oil in the oil chamber of the pump. In the present 60 construction we have mounted in the oil chamber a weight 14, the movements of which control both the admission of air to the oil chamber and the exhausting of the air therefrom. The controlling device or

valve, in the form here shown, comprises a casing 15 which is mounted on a bracket 16 rigidly secured to the head 9 of the casing 1 and, in the present instance, clamped to the upper end of the pipe 11. If desired, 70 the clamping collar 17, which forms a part of the bracket, may be utilized to support the pipe 11 on the head 9. The casing 15 of the combined inlet and exhaust valve has formed therein a conduit or chamber 18 75 which communicates by means of a pipe 19 with the air pipe 8 leading to the oil chamber. This chamber or conduit 18 also communicates with a pipe 20 which is connected with a source of supply of air under pressure, such as a pump or container in which the air is stored. No source of supply is shown in the present drawings as it is not necessary to an understanding of the invention. The chamber or conduit 18 also 80 communicates with an exhaust port 21 formed in the casing 15. The flow of air through the pipe 20 to the chamber 18 and from the chamber 18 to the exhaust port 21 is valve-controlled and, in the present instance, the inlet or supply pipe 20 and the exhaust port are arranged near the opposite ends of the casing 15 and are connected with the chamber 18 by means of ports 22 and 23, respectively, which ports are 85 controlled by valve members 24 and 25, respectively, the valves having valve stems 26 and 27 mounted in longitudinal guideways formed in the casing 15. Springs 28 and 29 act on the respective valves to move them 90 toward their seats and when unrestricted will serve to hold both valves closed.

Means are provided for causing the valve 24 to be opened when the fluid rises around the weight 14 to a certain predetermined 105 position and for causing the valve 25 to be opened, and the valve 24 closed, when the fluid lowers around the weight to a predetermined position. This means may be of various kinds but, in the present instance, the valves are shifted by means of air pressure derived from the supply line 20. To this end the valve casing is provided with a cylinder 30 in which is mounted a piston 31 of greater area than the valve 24 or 25 110 arranged, when moved in one direction, to engage the stem 26 of the valve 24 and when moved in the other direction to engage and operate the stem 27 of the valve 25. The air pressure on the piston 31 will be sufficient to overcome the air pressure on the valve 24 or 25 and the resistance of the corresponding spring 28. In the present instance this piston is hollow at both ends to 115 receive bosses 32 and 33 which extend into the cylinder at the opposite ends thereof and in which are formed the guideways for the valve stems 26 and 27. Communicating with the cylinder 30 at the opposite ends thereof are two inlet ports 34 and 35. The 120

130

port 34 is adapted to communicate with a conduit 36 which is connected by a passageway 37 with the air supply conduit 20. The passageway 36 is normally closed by means of a check valve 38. The inlet port 35 for the cylinder 30 communicates with a conduit 39 which is connected by a by-pass 40 with the conduit 36 and, consequently, with the supply line. The conduit 39 is also controlled by a check valve, 41, which is normally held closed by the pressure of the air within the conduit. The valve casing is here shown as provided with a recess 42 arranged between the two conduits 36 and 39.

10 Slidably mounted in the casing on opposite sides of the recess are plungers 43 and 44, the outer ends of which extend into the recess 42 and the inner ends of which are arranged adjacent to the balls of the check valves 38 and 41. Pivotally mounted on the casing above the recess 42 is a lever 45 having below its axis a finger 46 extending into the recess 42 and so arranged that when the lever is rocked in one direction the finger 25 will engage the plunger 44 and when the lever is rocked in the opposite direction the finger will engage the plunger 43. When the finger 46 engages the plunger 44 it shifts the same longitudinally and unseats 30 the valve 41, thus permitting the air to pass about the valve through the inlet port 35 to the cylinder 30, thereby shifting the piston to the left in Fig. 3, unseating the inlet valve 24, and permitting the air to flow 35 from the supply line 20 through the conduit or chamber 18, conduit 19 and pipe 8 to the oil chamber in the casing 3. When the lever is rocked in the opposite direction the plunger 44 is released, the ball valve permitted to seat under air pressure and subsequently the finger 46 will engage the plunger 43 and unseat the valve 38, thus permitting the air to enter the cylinder 30 at the opposite end of the piston, thereby shifting 40 the piston to the right, in Fig. 3, unseating the exhaust valve 25 and permitting the air which has been forced into the oil chamber under pressure to escape therefrom. To exhaust the air from the cylinder 30 and 45 permit the movement of the piston in one direction or the other relief ports 47 and 48 are provided to connect the ports 34 and 35 with the atmosphere. These relief ports are so arranged, however, that when either 50 plunger, 43 or 44, is in a position to unseat its check valve, it will extend across and close the corresponding relief port and when this plunger is in its retracted position, the body of the plunger will be moved out of 55 alinement with the relief port, thus opening the same and connecting it with the corresponding inlet port for the cylinder. The length of the piston is such that when the central portion thereof is in engagement 60 with one of the bosses 32 or 33 the adjacent end of the piston will be spaced slightly away from the end wall of the cylinder, thus permitting air to enter from the inlet ports, 34 or 35, back of the piston. The piston is preferably provided in its outer wall near 70 each end thereof with annular grooves 49 which are connected with the interior of the cylinder by small ports 50. Packing rings are mounted in these grooves and the pressure within the cylinder acts on the rings, 75 through the ports 50, and compresses the rings outward into engagement with the wall of the cylinder.

The movement of the lever 45 is controlled by means of the weight 14 and, to this end, 80 the lever is provided with arms 51 and 52 extending in opposite directions therefrom in a line transverse to the axis of the lever. One of these arms, in the present instance, the arm 51, is connected with the weight, 85 preferably by means of a wire 53. The other arm, 52, is provided with a counterweight 54. Normally, the weight is heavier than the counterweight. However, as the fluid rises around the weight its weight will 90 gradually decrease until the counterweight is able to move the weight upward. The well known principle of Archimedes is utilized. It will be apparent that as the weight rises the lever 45 will be rocked about its 95 axis by the counterweight 54, thus causing the finger 46 to engage the plunger 44 and cause the opening of the valve 24 to admit air to the chamber. As the oil is forced out of the chamber the weight 14 will finally 100 move downward against the action of the counterweight 54 and thus rock the lever 45 in the opposite direction, causing the air to be exhausted from this chamber, as above explained. It should be noticed that the action of the valves 24 and 25 is successive. One is fully closed before the other is opened. To secure a quick positive action of the valve the lever 45 is provided with a weight 55 which is lifted as the lever is 105 rocked through the first portion of its movement and, when the lever has been moved far enough to carry the weight past its center of gravity, will move quickly to the limit of its movement in the direction in which 110 it has been started. The arm 51 of the lever may be connected with the wire 53 in any suitable manner. It is preferable, however, that a rod be interposed between the arm and the wire in order that the opening 115 through which it extends into the pipe 8 may be more readily packed. We have, therefore, mounted on the upper end of the pipe 8, and preferably on the coupling between the pipe 8 and the pipe 19, two parallel guide 120 rods 56 on which is slidably mounted a cross head 57, this cross head having secured thereto a rod 58 which extends through a stuffing box 59 in the upper end of the coupling and has the wire 53 fastened there- 125 130

to at a point within the pipe 8. The cross head 57 is connected with the end of the arm 51 and this connection preferably comprises a spring 60 which serves to cushion the movements of the parts and prevent undue strain thereon and to permit the quick movement of the lever in one direction.

If the wire were attached to the weight before the latter was inserted in the well it 10 would be necessary to string the sections of the air pipe onto the wire as they were placed in position in the well and, in the case of a deep well, this would cause a great deal of difficulty. We have, therefore, provided means whereby the connection 15 between the wire and the weight may be made after the weight is in position.

The weight, which is here shown as a meter cylinder, has secured to its upper end 20 a rod 61 to which is secured a coupling member comprising a tubular casing 62 and having at its upper end an inwardly extending annular shoulder 63, the upper and lower faces of which are beveled. Arranged 25 within the tubular casing 62 is a series of jaws 64 having their upper ends beveled on both the inner and outer sides and provided with inwardly extending shoulders 65 which, when the several jaws are in engagement one with the other, constitute an annular shoulder. A spring 66 is confined in the 30 casing and exercises an upward pressure on the jaws 64, causing the beveled upper ends thereof to engage the beveled shoulder 63, which forces them inward. Coöperating 35 with this coupling member is a second coupling member which comprises a shank 67 having at its lower end a tapered head 68 which is provided at its upper end with a 40 square shoulder. This head is of such a diameter that it will pass through the opening in the upper end of the casing 62 and its tapered end will engage the tapered inner walls of the jaws 64. The weight of the 45 coupling member is sufficient to overcome the tension of the spring 66 and the jaws will be forced downward and as they move away from the beveled shoulder 63 will be spread apart to permit the head 68 to pass 50 between the same. As soon as the shoulder of the head has passed the shoulder 65 of the jaws 64 the spring 66 will again move the jaws upward against the beveled shoulder 63, closing them by the shank 67 with the shoulder 65 in opposed engagement with 55 the shoulder of the head 68, thus firmly connecting the two coupling members, and inasmuch as the second coupling member is secured to the wire 53 it will be apparent that 60 the wire is likewise, in this manner, connected with the weight. The size of the casing 62, relative to the pipe in which it is mounted, is such that when the arrow like coupling member drops down to the pipe 65 its tapered end necessarily enters the up-

per end of the casing. In order that the coupling members may be separated to permit the removal of the wire without the removal of the weight, a sleeve 69 may be placed about the wire and allowed to move along the same into the well. This sleeve is of such a diameter that it will enter the upper end of the casing 62 and has its lower end beveled to engage the beveled edges of the jaws and force the same apart, the 70 weight of the sleeve being sufficient to compress the spring 66, and thus permit the head 68 of the upper coupling member to be withdrawn from the casing 62.

When the weight has moved downward 80 to reverse the flow of air through the pipe 8 there still remains in the oil chamber more or less oil. By restricting the exhaust of the air, that is, permitting the same to exhaust slowly, the air in the chamber will be permitted to expand and will force out of the chamber an additional quantity of the oil. The exhaust of the air may be restricted in any suitable manner, as by the use of an ordinary air valve 70 which can be adjusted to 85 regulate the quantity of air that passes through the same. As it requires a considerable length of time for the chamber to fill with oil it will be apparent that the exhaust of the air can be restricted to a considerable 90 extent and, after it has ceased to expand, it will still escape fast enough to prevent any interference with the entrance of the oil into the chamber. When the apparatus is working normally it is so adjusted that the lower 95 end of the pipe 10 is always fluid sealed. This prevents air from mixing with the oil and spoiling the same.

The operation of the mechanism will be readily understood from the foregoing description and it will be apparent that the operation of the pump is automatically controlled by the rise and fall of the oil in the oil chamber, and further, that the mechanism by which this is accomplished is of a 105 simple, durable construction and is of such a character that it will require very little attention to keep it in operative condition.

While we have shown and described one embodiment of our invention it will be understood that this has been chosen for the purposes of illustration only, and that we do not desire to be limited to the details of construction shown and described, for obvious modifications will occur to a person 110 skilled in the art.

Having thus fully described our invention, what we claim as new and desire to secure by Letters Patent, is:—

1. In a pump, a casing having a chamber 125 communicating with a source of fluid supply, an outlet therefor, a valve casing communicating with said chamber with a source of compressed air and with an exhaust, independently operable valves controlling the 130

- admission of compressed air and exhaust, means controlled by compressed air for operating said valves, and means controlled by the rise and fall of fluid in said chamber 5 for operating said valve-operating means, said fluid-controlled means comprising a weight in said chamber operatively connected to said valve operating means, and means embodying a force working in opposition to 10 said weight.
2. In a pump, a casing having a chamber communicating with a source of fluid supply and provided with an outlet, said chamber communicating with a source of compressed 15 air, a valve member located in said communicating portion, and compressed air means for opening and closing said valve to admit compressed air to said chamber, said compressed air means comprising a piston 20 operatively associated with said valve member, passages connecting one end of said piston with a source of compressed air and with an exhaust, said passages being independently controlled by separate 25 valves, and means controlled by the rise and fall of the fluid within said chamber for operating said valves.
3. In a pump, a casing having a chamber communicating with a source of fluid supply, said chamber having an outlet, a valve casing communicating with said chamber with a source of compressed air and with an exhaust, and means for controlling the admission of compressed air and the exhaust, said means comprising valve members, a piston for controlling the same, passages connecting the ends of the piston with a source of compressed air and with an exhaust, valves controlling the admission of 35 compressed air and the exhaust in said passages, and means for operating said last-mentioned valves.
4. In a pump, a casing having a chamber communicating with a source of fluid supply, a discharge pipe for said chamber, a valve casing having a chamber communicating with said first-mentioned chamber, with a source of compressed air and with an exhaust, a valve controlling the admission 45 of compressed air, an exhaust valve, said valves being independently mounted in said valve casing and arranged to operate one at a time, compressed air means for operating first one valve and then the other, and means for controlling the admission of 50 compressed air to said compressed air means.
5. In a pump, a casing having a chamber communicating with a source of fluid supply, a discharge pipe leading from said chamber and an air conduit leading to said chamber, an inlet valve to control said conduit, an exhaust valve, springs tending to 60 keep said valves normally closed, said valves being independently mounted and arranged 65 to operate one at a time, compressed air means for operating first one valve and then the other, and means for controlling the admission of compressed air to said compressed air means. 70
6. In a pump, a casing having a chamber communicating with a source of fluid supply, a discharge pipe leading from said chamber, an air conduit communicating with said chamber, valves controlling the admission of compressed air and the exhaust thereof, said valves being independently operable and arranged to operate one at a time, air pressure means for operating said valves, and means comprising a weight 75 mounted in said chamber, and controlled by the rise and fall of fluid therein for actuating said air pressure means. 80
7. In a displacement pump, a casing having a chamber communicating with a source of fluid supply, a discharge pipe leading therefrom, a controlling device comprising a casing having a chamber connected with said first-mentioned chamber and having ports leading to a source of compressed air 85 and to an exhaust, valve members to control said ports, said valve members being independently mounted and spring controlled, a cylinder, a piston mounted in said cylinder, said cylinder having ports at the opposite ends thereof in communication with said source of compressed air, valves controlling said last-mentioned ports, and means to operate said last-mentioned valves 90 to cause said piston to move said valve members. 100
8. In a pump, a casing having a chamber communicating with a source of fluid supply, said chamber having an outlet, said chamber communicating with a source of compressed air, a valve member located in said communicating portion and compressed air means for opening and closing said valve to admit compressed air to said chamber, said compressed air means comprising a piston 105 operatively associated with said valve member, passages connecting one end of said piston with a source of compressed air and with an exhaust, said passages being independently controlled by separate valves, 110 and means for operating said valves.
9. In a pump, a casing having a chamber communicating with a source of fluid supply, said chamber also having an outlet, a valve casing communicating with said chamber with a source of compressed air and with an exhaust, valves controlling the same and means for controlling said valves, 115 said means comprising a cylinder, conduits connecting the opposite ends of said cylinder with a source of air supply, check valves interposed in said conduits between the cylinder and the source of air supply, said conduits also being provided with exhaust ports, plungers to open the respective check 120 valves, 125 and means for operating said valves.
10. In a pump, a casing having a chamber communicating with a source of fluid supply, said chamber also having an outlet, a valve casing communicating with said chamber with a source of compressed air and with an exhaust, valves controlling the same and means for controlling said valves, 130 said means comprising a cylinder, conduits connecting the opposite ends of said cylinder with a source of air supply, check valves interposed in said conduits between the cylinder and the source of air supply, said conduits also being provided with exhaust ports, plungers to open the respective check valves.

valves, said plungers also constituting valves for said exhaust ports, means for operating said plungers, and a piston mounted in said cylinder for operating said first-
5 mentioned valves when the plunger-operating means is actuated.

10. In a pump, a casing having a chamber provided with a valve-controlled inlet which communicates with a source of fluid supply, said chamber also having an outlet, an air pipe connected with said chamber, a valve casing having a chamber connected with said air pipe and having ports leading to a source of supply of air under pressure
15 and to an exhaust, valve members to control the respective ports, an actuating device for said valve members comprising a cylinder, and valve-controlled conduits connecting the opposite ends of said cylinder with said source of air supply, a piston mounted in said cylinder, and means connected with the respective valve members and extending into the opposite ends of said cylinder in the path of said piston, whereby the movement
20 of said piston in one direction will open one of said valves and in the other direction will open the other of said valves, a lever pivotally mounted on said valve casing, and means controlled by the movement of said
25 lever for opening one or the other of said valve-controlled passages.

11. In a pump, a casing having a chamber provided with a valve-controlled inlet which communicates with a source of fluid supply, said chamber also having an outlet, an air pipe connected with said chamber, a valve casing having a chamber connected with said air pipe and having ports leading to a source of supply of air under pressure and
35 to an exhaust, valve members to control the respective ports, an actuating device for said valve members comprising a cylinder, conduits connecting the opposite ends of said cylinder with said source of air supply,
40 check valves to control the respective conduits, plungers to open the respective valves, a lever having a part arranged to engage one of said plungers when said lever moves in one direction and to engage the other of said
45 plungers when the lever moves in the other direction, a piston mounted in said cylinder, and parts connected with the respective valve members and extending into the op-

posite ends of said cylinder and into the path of said piston.

55

12. In a displacement pump, the combination, with a pump chamber, of a controlling device comprising a casing having a chamber connected with said pump chamber and having ports leading to a source of supply for air under pressure and to an exhaust, valve members to control said ports, a cylinder arranged between said ports, stems connected with the respective valve members and extending into the opposite ends of said cylinder, a piston mounted in said cylinder, said cylinder having ports at the opposite ends thereof adapted for communication with said source of air supply, valves controlling said communication, valve-actuating members, a lever pivotally mounted on said casing and having a part arranged to engage one of said valve actuating members when the lever moves in one direction and to engage the other of said valve-actuating members when the lever moves in the other direction, and means to actuate said lever.

60

13. In a pump, a casing having a chamber communicating with a source of fluid supply, said chamber being provided with an outlet, an air pipe connecting said chamber with a source of compressed air, a valve interposed in said air pipe, and compressed air means for opening and closing said valve, said compressed air means comprising a cylinder having a piston therein for operating said valve, a conduit connecting said cylinder adjacent one end of the piston with a source of compressed air, said conduit being valve-controlled, an exhaust port for exhausting air from the said end of said piston, and a plunger for actuating said last-mentioned valve, said plunger constituting means for opening and closing said exhaust port.
